UNITED STATES PATENT OFFICE.

LORAIN J. FENTON, OF DETROIT, MICHIGAN, ASSIGNOR TO THE INTERNATIONAL STEEL TIE COMPANY, OF CLEVELAND, OHIO, A CORPORATION OF DELAWARE.

RAILROAD-TIE CLAMP FOR STREET RAILWAYS.

Application filed September 24, 1928. Serial No. 307,876.

This invention relates generally to a rail fastening element or clamp and more particularly to a jaw type tie clamp which is particularly adapted for use in constructing 5 street or boulevard railways and which is also well adapted for use with steel railroad ties of the twin type.

The main object of the invention is to provide a simple and efficient rail clamp which 10 is particularly adapted for use in detachably securing a rail to a railroad tie or other rail supporting member which is embedded in the concrete and disposed below the road surface and which also is readily accessible to 15 permit access to the bolt which holds the clamp and rail in place.

Another object of the invention is to provide a rail clamp of the character described which can be made in one piece and which 20 is well adapted for quantity production at a comparatively low cost.

Further and more limited objects of the invention will appear as the description proceeds and by reference to the accompanying 25 drawing in which Fig. 1 is a vertical sectional view disclosing a railroad rail secured in place by a pair of rail clamps constructed in accordance with my invention and Fig. 2 is a fragmentary top plan view of the tie plate 30 with the rail secured in place.

Referring now to the drawings, the reference character 1 designates the rail supporting portion of a steel tie of the twin type and which is provided with a pair of oppositely 35 disposed T-shaped openings 2 which are spaced apart a distance substantially equal to the width of the base of a standard rail. There are preferably four such openings disposed two on each side of the rail, although 40 only two are shown. The rail clamps 3, which form the main feature of this invention, consist essentially of a steel forging shaped in section, as shown most clearly in Fig. 1. Each rail clamp has a right angularly disposed portion 4 which for convenience will 45 be referred to as the heel. The under surface of each clamp has a flat bearing surface 5, a recessed portion 6 through which extends a cylindrical opening 7, and an angular recess 50 or notch 8 adapted to receive a portion of the base of the rail therein.

Each clamp 3 is inserted within the opening 2, as shown in Fig. 1 and is secured therein by means of a bolt 9 and nut 10. The head

11 of the bolt 9 is substantially rectangular 55 in shape and of such size that the head when in one position may be inserted through the opening 2 and then turned at right angles so as to engage beneath the edges of the T-shaped opening, as shown in dotted lines in 60 Fig. 2. When it is desired to secure a rail to the tie, the rail is placed on the tie in the position shown in Fig. 1 and the clamps inserted within the openings as shown, the base 65 of the rail engaging in the angular recesses 8. Each clamp 3 has an upstanding tubular portion 3^a through which the stem or neck of the bolt 9 extends. The tubular portion 3^a is preferably cast integral with the clamp.

By screwing down on the nuts 10 which 70 bear against the top of the tubular portions 3^a, the clamps will be pulled tight against the rail to securely fasten the rail to the tie. The flat bearing surfaces 5 of the clamps bear on the top of the tie at the points *a*—*a* and the 75 heels 4 of the clamps project through the openings 2 and bear against the rear face thereof and serve to guide the clamps and to hold the same square with the base of the rail. The rail clamps being spaced apart as 80 shown, serve to maintain rails parallel with each other. It will thus be seen that the clamps pivot about the points *a*—*a* and act as levers of the second class and serve to 85 secure the rail against displacement with respect to the tie. Disposed along each rail and preferably welded to the tie plates are a pair of downwardly converging stringers or baffle plates 12 and 13 which form a trench or channel along the rail which is filled with 90 a readily removable road forming material up to the level of the remaining portion of the road surface.

In order to provide access to the bolts 9, I dispose over the top of each of the nuts 10 95 a cap or block 14 of readily removable material such as lead, the top of which is buffed off so as to be flush with the road surface. Should the rail clamp become loosened during the life of the track, the clamp can be 100 tightened by removing the cap 14, thereby permitting access to the nuts 10 without disturbing any other portion of the road surface. Should it be desired to remove the rail for repair or replacement, the material filling 105 the trenches is removed and the rail clamps disconnected. The rail may then be removed leaving the bolts 9 in place.

Various changes may be made in the details of construction without departing from the spirit of the invention and it is understood that my invention is limited only in accordance with the scope of the appended claims.

It will now be clear that I have provided a rail fastening element which will accomplish the objects of the invention as hereinbefore stated.

Having thus described my invention, what I claim is:

1. In a street railway road construction, the combination of a road surface having a trench therein adapted to be filled with a readily removable road forming material, rail supporting members disposed within the said trench, a rail supported by said rail supporting members, rail clamps for connecting said rail with said rail supporting members, bolts connecting said rail clamps with said tie plate, said rail clamps having hollow extensions thereon opposite said bolts terminating adjacent the top of said trench whereby to permit access to said bolts without removing the material filling said trench.

2. In a street railway road construction, the combination of a road surface having a trench therein adapted to be filled with a readily removable road forming material, rail supporting members disposed within the said trench, a rail supported by said rail supporting members, rail clamps for connecting said rail with said rail supporting members, bolts connecting said rail clamps with said tie plate, said rail clamps having hollow extensions thereon opposite said bolts terminating adjacent the top of said trench whereby to permit access to said bolts without removing the material filling said trench, and a removable cap secured over the top of each of said tubular extensions, the upper surface of said caps being substantially flush with the road surface.

3. In a street railway road construction, the combination of a road surface having a trench therein, of rail supporting members secured within said trench, a rail arranged within said trench and resting on said rail supporting members, rail clamps connecting said rail with said rail supporting members and having hollow extensions thereon extending to a point adjacent the top of said trench, bolts extending through said hollow extensions and securing said rail clamps in place.

4. In a street railway road construction, the combination of a road surface having a trench therein, rail supporting members secured within said trench, a rail supported by said rail supporting members, rail clamps including bolts for securing said rail in place, a readily removable road forming material filling said trench, said rail clamps having hollow extensions thereon extending to a point adjacent the top of said trench where-

by to permit access to said bolts without removing the material filling the trench.

5. The combination of a tie having openings therein spaced apart, of rail clamps secured over said openings, each clamp having a heel portion projecting into the opening, a bolt extending through said clamp and arranged within said opening, one side of said clamp having a recess adapted to receive a portion of a rail therein, the said heel portion serving as a bearing surface and as a means for holding the clamp in engagement with the rail, each clamp having a hollow upstanding extension thereon through which the stem of the bolt extends.

6. The combination of a steel tie having openings in the upper surface thereof, of rail clamps secured over said opening, each clamp having a heel portion projecting into the opening, a bolt extending through each clamp and having a head adapted to engage beneath the edges of the opening, each clamp on the side opposite from said heel portion having an angular recess adapted to receive a portion of a rail therein, each clamp having a hollow upstanding extension thereon through which the stem of the bolt extends.

7. The combination of a steel tie having a pair of oppositely disposed openings therein spaced apart a distance substantially equal to the width of the base of a standard rail, each opening being substantially T-shaped, a rail clamp secured within each of said openings, each rail clamp having a heel portion projecting into the opening and adapted to bear against the rear face thereof, each clamp having a hollow upstanding extension thereon through which the stem of the bolt extends.

8. A rail fastening device of the character described adapted to be secured to a tie plate and comprising a clamp having an angular recess at one side thereof adapted to receive a portion of a rail therein and having an opening therein adapted to receive a bolt therethrough for securing the clamp to a tie plate, the opposite side of said clamp having a heel portion extending substantially at right angles to said opening and adapted to project into an opening in the tie and having a bearing surface on its under side between said heel portion and opening, said clamp having a hollow upstanding projection thereon through which the stem of the bolt extends.

9. A rail fastening device for use with steel ties comprising a clamp adapted to be positioned over an opening in a tie plate and having a heel portion adapted to project into the opening, said clamp having an opening therein disposed adjacent the center thereof and adapted to receive a bolt therethrough and a bearing surface between said opening and heel portion, one edge of said clamp having a recessed portion adapted to receive a

rail therein, said clamp having a hollow upstanding projection thereon through which the stem of said bolt extends.

10. A rail fastening device of the character described comprising a clamp having an angular recess at one side thereof adapted to receive a portion of a rail therein, the opposite side of said clamp having a heel portion extending at an angle thereto and adapted to project into an opening in a tie plate, said clamp being provided with an opening adapted to receive a bolt therethrough for securing the same to a tie, and a bearing surface between said opening and heel portion, said clamp having a hollow upstanding projection thereon through which the stem of said bolt extends.
11. A rail clamp comprising a steel forging substantially L-shaped in cross section and having an opening therein adapted to receive a bolt therethrough, said clamp having a hollow upstanding projection thereon through which the stem of said bolt extends.
12. The combination of a steel tie having oppositely disposed pairs of T-shaped openings therein, of rail clamps disposed over said openings, a bolt extending through each of said clamps, each bolt having a head shaped to engage beneath the edges of the opening, each clamp having a heel portion projecting

into said opening and adapted to bear against the face of the opening, the head of each bolt being of such size and so shaped that it may be inserted through said opening and then turned at right angle whereby to engage beneath the edges of the opening, said clamp having a hollow upstanding projection thereon through which the stem of said bolt extends.

13. The combination of a tie having a plurality of substantially T-shaped openings therein, of a rail clamp secured over each of said openings, each clamp having a heel portion projecting into the opening and loosely arranged therein and adapted to bear against the rear edge thereof, a bolt extending through each clamp and having a head adapted to engage beneath the opposite edges of the opening, the edge of each clamp opposite said heel portion being provided with an angular recess adapted to receive a portion of a rail therein, and means for tightening said bolt to secure a rail to said tie plate, said clamp having a hollow upstanding projection thereon through which the stem of said bolt extends.

In testimony whereof, I hereunto affix my signature.

LORAIN J. FENTON.
